UNITED STATES PATENT OFFICE.

ENRIQUETA CHACON, OF NEW YORK, N. Y.

DESIGN FOR A PIN.

47,452.

Specification for Design. Patented June 15, 1915.

Application filed May 3, 1912. Serial No. 694,966. Term of patent 7 years.

To all whom it may concern:

Be it known that I, ENRIQUETA CHACON, a subject of the King of Spain, residing at New York, in the county of New York and State of New York, have invented an original and ornamental Design for Pins, of which the following is a specification, reference being had to the accompanying drawing, forming a part thereof.

The figure is an elevation of a pin showing my new design.

I claim:

The ornamental design for a pin as shown.

ENRIQUETA CHACON.

In the presence of—

THOMAS BOLT,

IDA LINDEMAYER.
